HOT LIQUID PUMP

Earl B. Schwenk, Seattle, Wash.

Application May 15, 1946, Serial No. 669,968

2 Claims. (CL. 103—44)

1

This invention relates to a pump that is particularly well adapted for pumping hot liquid.

An object of this invention is to provide a pump that will pump hot liquid efficiently without damage to the pump.

Much difficulty is experienced in the operation of pumps that handle hot liquid on account of the damaging effect of the heat on parts of the pump, such as cup leathers and the like.

It is an object of this invention to provide an efficient pump in which the hot liquid that is being handled is efficiently pumped past a series of check valves without passing through the pump or coming into heat exchanging contact with the operating parts of the pump.

Another object of this invention is to provide a pump in which an upright conduit filled with cool liquid is connected at its upper end with another conduit through which hot liquid is being pumped and at its lower end with pulsator mechanism, said upright liquid conduit being of substantial length and the liquid in said upright conduit constituting a liquid plunger of at least twice the volume displaced by each stroke of the pulsator said liquid plunger being cool and serving as a barrier to prevent an objectionable amount of heat from the hot liquid from reaching the pulsator.

Another object is to provide a pump of this type in which the liquid forming the upright liquid plunger is of greater specific gravity than the hot liquid which is being pumped and in which this difference in specific gravity may be due solely to a difference of temperature between the liquid forming the liquid plunger and the liquid being pumped or may be due to the use, for the liquid plunger, of a liquid that has a greater specific gravity than the liquid being pumped when the temperatures of the two liquids are equal.

Another object is to provide a pump of this type in which the conduit wherein the liquid plunger operates is formed so as to provide a loop portion below the level of the pulsator and forming a sediment trap.

Another object is to provide a pump of this type that is especially well adapted for pumping hot water and one that can successfully use cooler water as a liquid plunger in pumping the hot water.

Other objects of the invention will be apparent from the following description taken in connection with the accompanying drawings.

In the drawings Figure 1 is a vertical sectional view illustrating

single acting hot liquid pump means constructed in accordance with this invention.

Fig. 2 is a plan view, on a smaller scale than Fig. 1, illustrating double acting pump means constructed in accordance with this invention.

Fig. 3 is a side elevation of the pump means shown in Fig. 2.

Referring first to Fig. 1, I show a pulsator of the reciprocating piston type which may be of standard construction. This pulsator comprises a cylinder 5 having therein a plunger 6 adapted to be reciprocated by any suitable means, such as an eccentric disc 7. The disc 7 is secured on a driven shaft 8 and is positioned within a yoke 9 that is rigid with the plunger 6 and carries a ring 10 that is rotatively supported on ball or roller bearings 11 and engages the yoke 9. A cup leather 12 may be provided on the end portion of the plunger 6 within the cylinder 5. Preferably the cylinder 5 has a head 13 and is provided adjacent said head 13 with two ports 14 and 15. A screw plug 16 is threaded into one of these ports such as the uppermost port 14. This screw plug is useful in that it may be removed to permit the escape of entrapped air, particularly at the time the pump is filled with liquid preparatory to being put into operation.

The lowermost port 15 is connected with a liquid plunger conduit comprising a downwardly extending loop portion 17, that extends downwardly and to one side, and another portion 18 that extends upwardly. A trap 19 is preferably provided at the lowermost portion of the loop conduit member 17 to catch any sediment that may tend to settle through the upright conduit member 18.

The upper end portion of the conduit member 18 is connected, as by a T member 20, with a hot liquid conduit member 21. Two check valves 22 and 23 are interposed in the conduit 21 on opposite sides of the T member 20. These check valves may be of any well known type that will efficiently prevent a flow of liquid in one direction and permit a flow of liquid in the opposite direction in the conduit 21.

The upright liquid plunger conduit 18 is of substantial length and this upright conduit 18 carries a volume of liquid that is at least twice as great as the volume of liquid that will be displaced by one stroke of the piston 6.

In the use of this device the pulsator and conduits 17 and 18 are filled with cool liquid, the portion of conduit 21 shown at the left of the valve 22 in Fig. 1 is connected with a source of supply of hot liquid and the portion of conduit

21 shown at the right of the valve 23 in Fig. 1 extends to any suitable location where hot liquid is to be delivered. Assuming the pulsator and conduits 17, 18 and 21 to be thus supplied with cool and hot liquid, then when the plunger 6 is reciprocated the cool liquid in the pulsator and conduits 17 and 18 will be reciprocated like a piston. As a result of this reciprocating action of the cool liquid hot liquid will be pumped continuously through the conduit 21 and past the check valves 22 and 23 in the direction indicated by the arrows in Fig. 1. After the device is functioning normally an amount of hot liquid about equal to the displacement of one stroke of the pump plunger 6 will descend into the upright conduit 18 upon each retractile stroke of the plunger 6 and an equal amount of hot liquid will be taken in past the valve 22. Upon the succeeding discharge stroke of the pulsator this hot liquid in the upright conduit 18 will be forced back up into the conduit 21 and an equal amount of hot liquid will be discharged past the check valve 23.

The hot liquid that enters the conduit 18 will not mix, to any substantial extent with the cooler liquid therein, but will stay on top of the cooler liquid. The cooler liquid, due to its lower temperature, has a greater specific gravity than the hot liquid and tends to remain in the bottom of the conduits 18 and 17. Thus it is practical to use a liquid plunger of cool water in the conduits 17 and 18 for pumping hot water through conduit 21.

In pumping hot water I find that very little heat reaches the pulsator, even during long periods of continuous operation, when cooler water is used as the liquid plunger and when the upright conduit 18 is of substantial length and when the volume of the upright conduit 18 is two or more times the volume of liquid displaced by one stroke of the pulsator plunger.

If the hot liquid that is being pumped carries heavy foreign substances, such as scale or sediment, that tend to settle in the upright conduit 18 these substances will be caught in the trap 19 and can be removed before they have a chance to enter the pulsator.

In some instances it may be desirable to have the liquid plunger formed of a liquid of substantially greater specific gravity than the liquid that is being pumped. For instance mercury can be used as a part of the liquid plunger in the lower portion of the conduit loop 17-18.

Figs. 2 and 3 show a two cylinder or duplex pulsator together with conduits and check valves arranged in accordance with this invention. Said Figs. 2 and 3 show two pulsator cylinders 25 and 26 having pistons 27 and 28 respectively reciprocable therein. The pistons 27 and 28 are integral with or otherwise fixedly secured to a common yoke 29. Yoke reciprocating means in the nature of an eccentric disc 30 on a driven shaft 31 provided with a ball or roller bearing ring 32 is shown. The ring 32 reacts against two opposed reaction surfaces 33 of the yoke 29 and reciprocates the yoke in a manner hereinbefore explained in connection with Fig. 1. The parts 25 and 33 inclusive are similar to corresponding parts shown in Fig. 1 and function in a similar manner.

Two liquid plunger conduits 34 and 35, each of J shape similar to the conduit 17-18 of Fig. 1, connect the respective pulsator cylinders 25 and 26 with a continuous run of hot liquid conduit 36. A hot liquid inlet pipe 37 and a hot liquid outlet pipe 38 are connected with the con-

tinuous conduit 36 at spaced apart points. Four check valves 39, 40, 41 and 42 are interposed in the continuous conduit 36, between the points of connection of pipes 34, 37, 35 and 38 with said conduit 36. The check valves 39, 40, 41 and 42 are positioned so they will permit liquid to flow in the directions indicated by the arrows but will prevent liquid from flowing in the opposite directions. In some instances it may be desirable to use two check valves in tandem instead of single check valves as shown, so that if one of said check valves should stick and fail to operate properly the other check valve of the pair will control the flow of liquid and the pump will continue to operate efficiently.

Unions 43 may be used in the conduits where necessary.

The operation of the double pump shown in Figs. 2 and 3 is similar to the operation of the single pump shown in Fig. 1. Each piston 27 and 28 operates a liquid plunger of cool liquid in the conduit 34 or 35 connected therewith. These pulsating liquid plungers alternately draw in hot liquid through the intake pipe 37 and discharge said hot liquid through the outlet pipe 38. The liquid in the conduits 34 and 35 will continue to operate at a relatively low temperature and will prevent objectionable heating of the pulsators 25 and 26 by the hot liquid that is being pumped through the conduit 36.

The foregoing description and accompanying drawings clearly disclose a preferred embodiment of this invention but it will be understood that this disclosure is merely illustrative and that changes may be made within the scope of the following claims.

I claim:

1. Means for pumping hot liquid comprising a continuous run of conduit; a hot liquid inlet pipe connected therewith; a hot liquid outlet pipe connected with said continuous run of conduit at a point spaced from the point of connection therewith of said hot liquid inlet pipe; two reciprocating plunger pulsators positioned below said continuous run of hot liquid conduit; two J-shaped conduits adapted to contain cooler liquid, each J-shaped conduit having a loop portion extending below one of said pulsators and having a shorter branch connected with said pulsator and having a longer branch connected with said continuous run of conduit, the points of connection of said longer branches with said continuous conduit being at opposite sides of said hot liquid inlet and outlet pipes; and four check valves in said continuous conduit positioned so that a check valve is interposed between each J-shaped conduit and each hot liquid pipe that connects with said continuous run of conduit, each of said check valves permitting a flow of hot water from said inlet to said outlet pipe and preventing a flow of hot water in the opposite direction.

2. Means for pumping hot liquid comprising a continuous run of conduit; a hot liquid inlet pipe connected therewith; a hot liquid outlet pipe connected with said continuous run of conduit at a point spaced from the point of connection therewith of said hot liquid inlet pipe; two reciprocating plunger pulsators positioned a substantial distance below said continuous run of hot liquid conduit; two J-shaped conduits adapted to contain cooler liquid, each J-shaped conduit having a loop portion extending below one of said pulsators and having a shorter branch connected with said pulsator and having a longer branch connected with said continuous run of conduit, the

points of connection of said longer branches with said continuous conduit being at opposite sides of said hot liquid inlet and outlet pipes, the volume of liquid carried by the longer branch of each conduit being at least twice as great as the volume of liquid displaced by one stroke of said pulsator; a sediment trap provided in the lowermost portion of the loop of each J-shaped conduit; and four check valves in said continuous conduit positioned so that a check valve is interposed between each J-shaped conduit and each hot liquid pipe that connects with said continuous run of conduit, each of said check valves permitting a flow of hot water from said inlet to said outlet pipe and preventing a flow of hot water in the opposite direction.

EARL B. SCHWENK.
